United States Patent

Des. 237,592
Patented Nov. 11, 1975

237,592

POUR SPOUT LID

Hubert E. Christian, Phoenix, Ariz., assignor to Dart
Industries Inc., Los Angeles, Calif.

Filed July 5, 1973, Ser. No. 376,570

Term of patent 14 years

Int. Cl. D9—07

U.S. Cl. D9—254

FIG. 1.

FIG. 2.

FIG. 3.

FIG. 4.

FIG. 5.

FIG. 6.

FIG. 1 is a top plan view of a pour spout lid showing my new design.

FIG. 2 is a front elevational view;

FIG. 3 is a rear elevational view thereof;

FIG. 4 is a bottom plan view thereof;

FIG. 5 is a side elevational view thereof; and

FIG. 6 is a cross-sectional view from line 6—6 in FIG. 1.

I claim:

The ornamental design for a pour spout lid, as shown and described.
